UNITED STATES PATENT OFFICE.

CHARLES LESTER PARMELEE, OF WEST ORANGE, NEW JERSEY, ASSIGNOR TO SINCLAIR REFINING COMPANY, OF CHICAGO, ILLINOIS, A CORPORATION OF MAINE.

CRACKING OF HYDROCARBON OILS.

Application filed October 8, 1924. Serial No. 742,347.

This invention relates to an improved process of cracking hydrocarbons for the production of lighter hydrocarbon oils, such as gasoline or pressure distillate, from heavier hydrocarbon oils.

More particularly, this invention relates to improvements in the operation of pressure stills in which the bulk of the oil being treated is maintained in a vaporizing chamber or bulk supply tank, and in which the oil is circulated from and to the body of oil in the vaporizing chamber or bulk supply tank through a heater. A cracking operation of this general character is described in United States Letters Patent No. 1,285,200 granted to the Sinclair Refining Company November 19, 1918, on the application of Edward W. Isom; and, from one aspect, the present invention may be considered an improvement upon the operation there described.

In cracking hydrocarbon oils by distillation under pressure, considerable amounts of heavy matter, such as carbon, tar, and the like, are formed. If these heavier materials are permitted to deposit in or upon the heating surfaces which are in contact with the heating gases or other heating medium, they tend to form a coating thereon which insulates the heating walls from the cooling effect of the circulating oil, with the result that the walls, or portions thereof on which the deposition has taken place, tend to become overheated; and as the overheating increases the deposition and that in turn contributes to further overheating, the heating surfaces are apt to be burnt and weakened and sometimes burst unless the overheating is noted in time and the still shut down or the fire diminished. This deposition of an insulating layer also materially diminishes the capacity of the heating surfaces. As cracking continues, the heavy matters tend to accumulate in the cracking system, and, if the oil is recirculated through the heating element, the tarry matter and carbon are again and again afforded opportunity to deposit, and so in fact deposit, upon the walls of the heating element.

In the operation of circulatory cracking stills of the character above referred to, the introduction of the hot vapor-laden and vaporizing oil into the bulk supply tank or vaporizing chamber, as it circulates from the heating element, tends to cause turbu-

lence or eddying in the bulk supply tank so that the vapors and light cracked constituents are incompletely liberated in the bulk supply tank, and so that such vapors and light cracked constituents as are not liberated are again carried through the heating element with the circulating oil where they are further subjected to a higher cracking temperature. The recirculation of such lighter constituents through the heater tends to result in overcracking, with accompanying increased production of heavy tarry matter and light incondensable gases at the expense of constituents desirable in the pressure distillate, and also tends to produce a pressure distillate unsaturated to an objectionable degree.

The present invention includes an improved method of operating circulatory pressure stills for cracking hydrocarbon oils in which the separation of heavy matter from the unvaporized oil is promoted before the unvaporized oil is recirculated through the heating element whereby only relatively clean oil passes through the heating element and deposition of carbon and tarry matter on the walls of the heating element is largely prevented or reduced. The invention also includes an improved method of operation in which the liberation of vapors and light cracked constituents from the hot oil circulating from the heater is promoted before the unvaporized oil is recirculated through the heating element whereby overcracking is avoided or reduced and whereby the quantity and quality of the pressure distillate may be improved. The invention also includes an improved method of operation for preventing or reducing contamination of returned reflux or fresh charging stock introduced during the progress of the cracking operation with carbon or tarry matter previously produced. Other features of the invention will appear hereinafter.

According to the present invention, the bulk supply tank is arranged to provide a receiving compartment for the hot oil and vapors from the heater, in which carbon and tarry matter tends to precipitate and in which the liberation of vapors from the hot oil is promoted, and a supply compartment for oil circulating to the heater to which unvaporized oil, relatively free from carbon and tarry matter and from vapors and light cracked constituents, is overflowed from the

receiving compartment. Heavy matter may be withdrawn from the receiving compartment from time to time. The vapors liberated may be subjected to a refluxing operation and the reflux returned to the supply compartment where it mixes only with the oil therein which is relatively clean and free from vapors and light cracked constituents. Fresh charging stock may be introduced into the supply compartment, and may be introduced into direct contact with the vapors in the refluxing operation and conducted to the supply compartment in admixture with the reflux. Circulation of the oil within the system may be effected by a forcing means, such as a pump, or by thermosiphonic action.

The invention will be further described in connection with the accompanying drawings illustrating two arrangements of apparatus adapted for the practice of the process of the invention, but it will be understood that the invention is illustrated thereby and not limited thereto.

In the accompanying drawings:

Fig. 1 is a diagrammatic view partly in section and partly in elevation of a still construction adapted for carrying out the invention, and

Fig. 2 is a fragmentary view of a modified still construction adapted for a modified way of carrying out the invention.

The apparatus shown in Fig. 1 comprises a furnace structure 3 having a fire-box 4, a vertical throat 5, a heating flue 6, and a stack flue 7. The heating flue 6 is provided with baffles 8 and 9, and a battery of tubes 10 extends vertically therethrough and is provided with upper and lower headers 11 and 12 respectively. A connection 13 is provided for returning a portion of the cooled products of combustion to flues underneath the fire-box 4 and at the base of the throat 5 whereby the fresh hot products of combustion from the burners 15 are somewhat diluted by the cooler products of combustion, thus diminishing the temperature and increasing the volume of the heating gases, avoiding overheating of the front tubes in the first pass, more evenly and efficiently heating the tubes throughout, and protecting the walls of the fire-box and furnace structure. The tank or drum 17 is a relatively long closed cylinder arranged with its long axis vertical and with its upper end extending well above the heating element in the furnace. The tank is divided by a vertical partition 18 which extends from the bottom thereof to a level substantially above the top of the heating element 10 dividing the lower portion of the tank 17 into a receiving or separating chamber 19 and an exhaust or supply chamber 20. The receiving compartment 19 is connected to the top manifold 21 of the top header 11 by a suit-

able return flow pipe 22. The supply compartment 20 is connected to the manifold 23 of the lower header 12 by a circulating line, which, as shown in Fig. 1, includes the horizontal pipe 24, vertical pipe 25, pump 26, vertical pipe 27 and horizontal pipe 28. In one way of carrying out the invention, the pump 26 may be dispensed with, and the pipe 24 directly connected with pipe 28 by a pipe 25' as shown in Fig. 2. The tank and pipe connections may with advantage be heat insulated. A tar line 30 provided with a valve 31, extends substantially to the bottom of the receiving chamber 19. A man-hole 32 is provided for cleaning out the compartment 19 when required. The pipe 33 having a valve 34 is connected to the lowest point of the bottom of compartment 19 for charging the still with oil in starting up and pumping out when the operation is discontinued, and a valved branch 35 therefrom connects to a T 36 between pipes 27 and 28 for withdrawing oil from these pipes between runs.

The upper end of the tank above the compartments 19 and 20 may, however, with advantage, be constructed of such volume and suitably equipped to constitute a reflux tower, and a separate tower dispensed with. The upper portion of the tank 17 is illustrated as provided with baffles 38 which may be of the type commonly employed in reflux towers. The vapor line 39 leading to the condenser is connected directly to the upper end of the tank. The lowermost baffle 38' is so disposed as to discharge any liquid thereon into the supply compartment 20. A valved line 40 and a sprayhead 41 are provided for the introduction of fresh charging stock into the upper end of the reflux tower, and this feed may or may not be supplemented by the introduction of oil through valved connection 47. The vapor line 39, condenser 42 and receiving drum 43, with its gas release line 44 and distillate drawoff 45, may be of the type commonly employed in connection with cracking stills. A pressure regulating valve 46 in line 39 between the reflux tower and the condenser may be employed for controlling and reducing the pressure in the still and reflux tower independently of the pressure in the condenser or the pressure may be reduced and regulated by suitable valves arranged beyond the condenser.

Briefly, the operation of the illustrated apparatus is as follows: Oil is circulated from the supply compartment 20 in the tank 17 through the heating tubes 10 and thence back to the separating compartment 19, either by means of a pump 26 or by thermosiphonic action, the vaporized oil collecting in the upper portion of the tank 17 and being subjected to reflux condensation therein, the resulting vapors passing

through vapor line 39 and condenser 42 to the receiver 43, the liquid distillate being drawn off through connection 45 and uncondensed gases through connection 44. Feed oil is introduced either through connection 40 into the head of the drum 17 or through connection 47 into the oil passing to the heating element 10 or through both connections. Reflux condensate, and admixed with any feed oil introduced through connection 40 is returned to the heating element through compartment 20. The pressure within the cracking system may be controlled by valve 46 or by control of the withdrawal of liquid distillate and uncondensed gases from the receiver 43. Condensation may be effected at atmospheric pressure, or at some predetermined intermediate pressure above atmospheric pressure.

The bulk of the oil being treated is contained in the tank 17 located away from the furnace 3 and is heated by circulating a stream of oil therefrom through the heating element 10 in the furnace and back to the tank. This circulating stream of oil is continuously withdrawn from the supply chamber 20 and flows through the described pipe connections to the heating element 10 in the furnace and thence through the upper return pipe 22 to the receiving or separating chamber 19. The circulation is advantageously effected by means of a pump 26, rapid circulation increasing the capacity of the still and being more efficient in keeping the heating tubes swept clean of deposits of carbon and tarry matter. Under proper conditions, however, the thermal effect in the heating element or battery of tubes, is sufficient to produce the required circulation. The furnace temperature and rapidity of circulation may be such as to maintain the oil in the tank 17 above the cracking temperature of the components of the oil treated which are to be broken down, or the oil may be subjected to the cracking temperature only as it passes through the heating tubes.

The volume of oil maintained in the system during normal operation is such as to keep the separating chamber 19 filled to the top thereof and overflowing into the supply chamber 20, and to keep sufficient oil in the supply chamber 20 to properly maintain the circulation. Where a circulating pump is employed, the level of oil in the supply chamber 20 is advantageously maintained considerably below that in the receiving chamber 19, as shown in Fig. 1, so that the oil flowing from compartment 19 to compartment 20 passes in a thin sheet or film down the partition 18 which is heated by the oil in the receiving chamber 19. This method of operation promotes the release of gas and vapors from the oil flowing downwardly over the partition. Where pump or forced

circulation is employed, the exact level of the oil in compartment 20 is not important provided it is sufficient to maintain proper circulation, but where thermal circulation is employed, the level of the oil in compartment 20 should be sufficient to maintain circulation, and is in general somewhat higher more closely approaching the oil level in compartment 19. Where thermosiphonic circulation is employed, the level of the cooler oil in compartment 20 must be such as to overbalance the column of hotter oil in the heating element 10 and in compartment 19. The decreased density of the hotter oil and the formation of gases and vapors in heating element 10 and the discharge of these gases and vapors in that portion of compartment 19 above the level of return pipe 22 tends to maintain circulation, but with thermal circulation, the level in compartment 20 must be higher than with pump circulation and usually must be maintained above the level of return pipe 22.

The oil from the return pipe 22 is discharged into the chamber 19 below the level of the oil therein but at a considerable distance above the bottom of the chamber. The upward movement of oil in the chamber 19 is relatively slow, due to the relatively large cross section of the column of oil in this chamber as compared to that of the oil stream entering it, thus affording a very favorable condition for the separation of any carbon or tarry matter formed in the passage of the oil through the heating tubes 10 or the pipe 22. That portion of the chamber 19 below the connection of pipe 22 thereto offers a quiescent zone in which the carbon and heavier tarry products separating from the circulating oil may settle out and deposit. The heavier products depositing in chamber 17 may be drawn off intermittently or continuously during the operation of the still through the tar line 30. The oil entering the chamber 19 is thus substantially freed of the heavy matter formed during the cracking operation and only relatively clean or clarified oil overflows into the supply chamber 20. Thus, though continuous recirculation of unvaporized oil is maintained through the heating element, the heaviest of the products formed are not returned to the heating element so that the tendency to deposition of tar and carbon is minimized.

By subjecting the oil vapors freed from the heated oil to reflux condensation in the upper part of the drum 17, any tendency to carry drops or particles of liquid oil into the reflux tower and tendency to puke, due to the constricted passage between the still and reflux tower as commonly designed, is obviated. The surfaces of the oil in chamber 19 and 20 and on the baffle above the oil level in chamber 20 are free and in unob-

structed communication with the vaporizing and refluxing space permitting a ready release of vapors and gases formed. By maintaining the level of the liquid in the chamber 5 19 above the heating element and the connections thereto, there is no opportunity for the formation of vapor pockets and the heating tubes and connections are kept full of oil throughout the operation. Reflux is deflected by the lowermost baffle 38' into the chamber 20, so that the tar and carbon free reflux is returned to the cracking operation without admixture with the hot oil containing heavy matter.

10 Fresh charging stock, likewise, is advantageously introduced into the still system subsequently to the separation of tar and carbon from the recirculated unvaporized oil. The fresh oil may be introduced through 15 connection 47 into the clarified oil flowing from compartment 20 through pipe 24, or it may be introduced through connection 40 at the upper end of the tank 17, or through both of these connections. Where the fresh 20 oil is introduced at the upper end of the reflux tower in the top of the tank 17, it assists in the reflux condensation and affords a convenient control of the still head temperature. The unvaporized fresh oil introduced 25 through connection 40, in admixture with any reflux formed in the upper end of the drum 17, is directed into compartment 20 by the lowermost baffle 38' without admixture with the unclarified oil in compartment 30 19.

The method of the present invention is of special value and application in connection with continuous or semi-continuous methods of operation in which fresh charging stock 35 is introduced during the progress of the cracking operation and in which tar is withdrawn to maintain the concentration of tarry constituents in the charge below an objectionable point. In carrying out the present 40 invention in connection with such processes, the tar is withdrawn as it is separated by precipitation from the circulating oil. For example, in the apparatus illustrated, tar may be withdrawn from the lower part of 45 compartment 19, where the tarry constituents tend to concentrate, in amount sufficient to prevent or retard increase in concentration of such constituents in the circulating charge during the course of the cracking operation.

50 It will thus be seen that this invention provides an improved method of operating circulatory pressure stills which is of particular advantage in prolonging the cracking operation by promoting the separation of carbon and tarry constituents from the circulating oil and by recirculating only a relatively clean or a clarified oil. The process of the invention also offers advantages in eliminating or reducing overcracking and the further decomposition of constituents desirable 55

in the pressure distillate. It will also be seen that this invention provides an improved method of handling reflux and of introducing fresh charging stock during the progress of the cracking operation. 70

The apparatus described herein is claimed in my co-pending application Serial #652,497, filed July 19, 1923.

I claim:

1. A process of cracking hydrocarbon oils 75 which comprises circulating oil from a supply chamber through a heating element to a separating chamber, subjecting the oil to a cracking temperature in the heating element and maintaining the oil in the separating chamber and that in the supply chamber in indirect heat exchanging relation, effecting a separation of carbon and tarry matter in the separating chamber and withdrawing the separated carbon and tarry matter, passing 80 the clarified liquid oil to the supply chamber, collecting the vapors liberated in the separating chamber and the supply chamber and subjecting them to a refluxing operation, introducing fresh oil into the refluxing opera- 85 tion and passing the admixed reflux and fresh oil from the refluxing operation to the supply chamber. 90

2. A process of cracking hydrocarbon oils which comprises circulating oil from a supply chamber through a heating element to a separating chamber, subjecting the oil to a cracking temperature in the heating element and maintaining the oil in the separating chamber and that in the supply chamber in 100 indirect heat exchanging relation, effecting a separation of carbon and tarry matter in the separating chamber and withdrawing the separated carbon and tarry matter, passing 105 the clarified liquid oil to the supply chamber, collecting and removing the vapors liberated in the separating chamber and supply chamber and introducing fresh oil to the supply chamber. 110

3. A process of cracking hydrocarbon oils which comprises introducing fresh oil to a supply chamber, circulating oil from the supply chamber through a heating element to a separating chamber, subjecting the oil to a cracking temperature in the heating element and maintaining the oil in the separating chamber and that in the supply chamber in indirect heat exchanging relation, effecting a separation of carbon and tarry matter in the separating chamber and withdrawing the separated carbon and tarry matter, passing the clarified liquid oil to the supply chamber, collecting the vapors liberated in the separating chamber and supply chamber and subjecting them to a refluxing operation, and returning the reflux to the supply chamber. 115 120

4. A process of cracking hydrocarbon oils which comprises circulating oil from a supply chamber through a heating element to 130

lecting and removing the vaporized oil from the upper part of the receptacle.

13. A process of cracking hydrocarbons which comprises circulating oil through a heating element, subjecting it to a cracking temperature therein, introducing the heated oil into a vertically disposed receptacle below the normal liquid level on one side of a partition dividing the lower part of the receptacle, effecting a separation of carbon and tarry matter in the body of oil on the same side of the partition, maintaining a lower liquid level on the other side of the partition and overflowing the clarified liquid oil across the partition, subjecting the vaporized oil to a refluxing operation in the upper part of the receptacle, directing the reflux condensate to the compartment with the overflowing oil in the lower part of the receptacle, and recirculating the oil therein through the heating element.

14. A process of cracking hydrocarbon oils which comprises circulating oil through a

heating element, subjecting it to a cracking temperature therein, introducing the heated oil into a vertically disposed receptacle below the normal liquid level on one side of a partition dividing the lower part of the receptacle, effecting a separation of carbon and tarry matter in the body of oil on the same side of the partition, maintaining a lower liquid level on the other side of the partition and overflowing the clarified liquid oil across the partition, subjecting the vaporized oil to a refluxing operation in the upper part of the receptacle, introducing fresh oil into the upper part of the receptacle, directing the unvaporized fresh feed oil and admixed reflux to the compartment in the lower part of the receptacle with the overflowing oil, and recirculating the oil in this latter compartment through the heating element.

In testimony whereof I affix my signature.

CHARLES LESTER PARMELEE.
